UNITED STATES PATENT OFFICE.

WILLIAM M. GARTON, OF BALTIMORE, MARYLAND, ASSIGNOR TO WILLIAM SWINDELL, WALTER B. SWINDELL, CHARLES J. B. SWINDELL, AND JOSEPH R. SWINDELL, ALL OF SAME PLACE.

DESIGN FOR A BOTTLE.

SPECIFICATION forming part of Design No. 18,390, dated June 19, 1888.

Application filed May 10, 1888. Serial No. 273,503. Term of patent 14 years.

To all whom it may concern:

Be it known that I, WILLIAM M. GARTON, a citizen of the United States, residing at Baltimore, Maryland, have invented a new and original Design for a Bottle, of which the following is a specification.

The bottle is of general quadrangular shape in cross-section, and has convex ends, round corners, and curved shoulders, the latter forming where they join the sides and ends of the bottle a well-defined or marked line, as described hereinafter.

The design is fully illustrated in the accompanying drawings, in which—

Figure 1 is a perspective view of the bottle. Fig. 2 is a side view. Fig. 3 is an end view, and Fig. 4 is a plan view, with the neck in section on the line 1 2, Fig. 2.

A is the body of the bottle, of general quadrangular shape in cross-section. D is the neck, and B are the shoulders. The sides a a of the body are flat, as shown in Fig. 4, and the ends

b b are each convex in form, the corners being rounded, as shown at c c. The shoulders B of the bottle are curved from the neck toward each end, as shown in Fig. 2, and where the shoulders join the sides and ends a well-defined sharp edge or marked line, d, is formed, giving the peculiar effect shown in Fig. 1.

I claim—

The herein-described design for a bottle, said design consisting of the body having flat sides a a, convex ends b b, rounded corners c c, and curved shoulders B, forming a well-defined line, d, where they join the sides and ends of the body, all substantially as shown and described.

In testimony whereof I have signed my name to this specification in the presence of two subscribing witnesses.

WILLIAM M. GARTON.
